FIG. 1.

FIG. 2.

INVENTOR

WILLIAM D. ENGELKE.

By *Bradbury & Baswell*
ATTORNEYS.

UNITED STATES PATENT OFFICE.

WILLIAM D. ENGELKE, OF ST. PAUL, MINNESOTA.

ASH HANDLER.

1,407,847.

Specification of Letters Patent. Patented Feb. 28, 1922.

Application filed January 15, 1920. Serial No. 351,532.

To all whom it may concern:

Be it known that I, WILLIAM D. ENGELKE, a citizen of the United States, residing at St. Paul, in the county of Ramsey and State 5 of Minnesota, have invented a new and useful Improvement in Ash Handlers; of which the following is a specification.

This invention relates to improvements in ash handlers, the primary object being to remove ashes from below the fire grates of locomotives and boilers to one side of the railway track or road bed or to a point distant from the boiler in an expeditious and efficient manner, not requiring rehandling of ashes 10 and cinders as heretofore and overcoming the many objections incident to dumping ashes in ash pits. A further object is to provide in a structure which will accomplish the above improved result, means whereby the apparatus can be made to deliver the ashes to either or both sides of the track or road bed, and further to control the operation of the apparatus manually from within the cab or adjacent to the cab of the locomotive.

In the accompanying drawing forming part of this specification, Fig. 1 is a side elevation of a portion of a locomotive showing its boiler, fire box and cab, and my invention applied thereto; Fig. 2 is an end elevation of the boiler and fire box illustrated in Fig. 1, showing my invention, in part, applied thereto; and Fig. 3 is a section of a detail taken on the line 3—3 of Fig. 2.

In the drawing, A indicates the boiler of the locomotive, mounted upon the usual truck wheels 10 having the usual steam dome 11. B indicates the cab and C the fire box containing the usual fire grate 12. Below the grate is the usual ash hopper 13. To the lower end of this hopper I attach an ash receptacle 14, which is divided by a transverse wall 15 into two compartments 16 and 17, the compartment 16 connecting with a downwardly and outwardly slanting ash chute 18 and the compartment 17 connecting with a downwardly and outwardly slanting ash chute 19, said chutes being directed in opposite directions across the road bed below the locomotive and being adapted to conduct the ashes and cinders on either or both sides of the track and road bed and away from any pit that may occur below the locomotive.

The upper ends of the compartments 16 and 17 are provided with hopper doors 21 and 22 which are adapted to be swung downwardly by their shafts 23 and 24 to admit

the ashes and cinders from the hopper into either receptacle 16 or 17 desired. When in horizontal (closed position), they hold the ashes and cinders from entering the receptacle then closed. The shafts 23 and 24 are journaled in the walls of the casing forming the receptacle 14 and are turned to open and close the doors by crank arms 25 and 26, connecting rods 27 and 28 and two manually operable lever handles 42 and 43 extending upwardly into the cab B in convenient position for an attendant to swing the same over a ratchet engaged quadrant 30 and adjust the position of the doors. The lower end 31 of the lever 43 is attached to the connecting rod 27 and the lower end 32 of lever 42 is connected to the connecting rod 28. The arrangement of the connections between the arms 42 and 43 and the door shafts 23 and 24 is such that either door can be closed. Thus the ash chutes will deliver ashes to either or both sides of the road bed according to when they are opened.

For the purpose of positively and quickly ejecting the ashes and cinders from the receptacle 14 through the chutes, I utilize a blast of steam pressure issuing from the steam dome 11 or a blast of water from below the water line in the boiler A. This is supplied by a pair of blast tubes 35 and 36 having their outlet ends arranged respectively in and adjacent to the chutes 19 and 18 and directed outwardly so as to blow the ashes and cinders outwardly from the chutes to either side of the road bed. The tube 35 is connected by a valved branch 37 with the steam dome and by a valved branch 38 with the boiler below its water line and the tube 36 is connected by a valved branch 39 with the steam dome and by a valved branch 40 with the boiler below its water line. Thus when the valved branch directly connected with the steam dome is opened, high pressure steam will blow the ashes through the chute thus effected, while if the valved branch connected with the boiler below its water line is opened, steam and water under pressure will blow the ashes outwardly through the chute effected.

In operation one or both of the compartments are opened and their companion blast tubes operated to quickly and efficiently expel ashes from the hopper. The entire device is simple in construction and effective in operation to remove ashes and cinders to either side of the road bed be-

low the locomotive. When desired deflectors 41 may be employed over the outer end of the chutes 18 and 19 to direct the ashes and cinders in a more direct downward direction.

It will be understood that my invention is equally applicable to stationary boilers or boilers of any type. It will save all labor used in removing ashes and cinders from 10 between rails, as well as prevent burning of ties. It will greatly lessen the expense of cinder pit construction and maintenance, as it will be possible to use the invention to deliver the ashes and cinders from the ash pan 15 of the engine or from below the grate of any fire grate to the cinder car, without shoveling by hand as is now done. My invention will also lessen to a great extent the amount of dust raised by fast moving trains by 20 delivering the cinders and ashes outside of the ends of the ties, which will place the dust and cinders outside of the force of suction of air caused by fast moving trains. While I have shown one particular arrangement of 25 parts on a locomotive, it will be understood that the arrangement of parts will be varied in accordance with the class and type of engine and boiler to which my invention is applied.

30 In accordance with the patent statutes I have described the principles of operation of my invention, together with the apparatus which I now consider to represent the best embodiment thereof, but I desire to have 35 it understood that the construction shown is only illustrative and that the invention can be carried out by other means and applied to uses other than those above set forth within the scope of the following claims.

40 Having described my invention, what I claim as new and desire to protect by Letters Patent is:

1. In combination with a locomotive boiler and fire grate, an ash receiver below said 45 grate having conveying means leading from the bottom of the receiver outwardly to either side of the road bed below the locomotive, means for directing the ashes from the fire grate to said ash receiver and a steam connection with said boiler arranged to blow 50 a blast of steam outwardly through said conveying means to eject ashes from said receiver to either side of said road bed.
2. In combination with a locomotive boiler 55 and fire grate, an ash receiver below said grate having lateral conveying means leading from the bottom of the receiver outwardly to either side of the road bed below

the locomotive, means for directing the ashes from the fire grate to said ash receiver and 60 a valved steam connection with said boiler arranged with its outlet adjacent to said conveying means and adapted to blow a blast of steam outwardly through said conveying means to eject ashes from said receiver entirely 65 to either side of said road bed, the valve of said steam connection being located within the cab of the locomotive, for the purposes specified.

3. In combination with a locomotive boiler 70 and fire grate, an ash receiver below said grate having a pair of ducts leading outwardly in opposite directions to discharge to opposite sides of the road bed below the locomotive, means for directing the ashes from 75 the fire grate to said ash receiver and valved steam connections with said boiler for said ducts, arranged to discharge steam into the respective ducts and outwardly therethrough and to eject ashes from said receiver to the 80 sides of said road bed.

4. In combination with a locomotive boiler and fire grate, a hopper below said grate, an ash receptacle into which said hopper connects, means for closing or opening the entrance into said receptacle, means for operating said closing and opening means to close or open said receptacle, said receptacle having conveying means leading outwardly to either side and transversely of the road bed 90 below the locomotive, and a valved steam connection with said boiler arranged with its outlet adjacent to said conveying means and adapted to blow a blast of steam outwardly through said conveying means to 95 eject ashes from said receptacle entirely to either side of said road bed.

5. In combination with a locomotive boiler and fire grate, a hopper below said grate, a pair of receptacles into which said hopper connects, each of said receptacles having a door closing its entrance, means for closing and opening said doors, said means being operable from within the cab of the locomotive and said receptacles having ducts leading 100 outwardly to opposite sides of the road bed below the locomotive, and valved steam connections with said boiler arranged with their outlets adjacent to said ducts to discharge steam into the respective ducts and outwardly therethrough and to eject ashes from 105 said receptacles to the sides of said road bed.

In testimony whereof, I have signed my name to this specification.

WILLIAM D. ENGELKE.
